Fig. 3

Fig. 5

Fig. 6

FIG. 1 is a top plan view of a grill having the top closed and internal parts in a partially extended position, showing my new design;

FIG. 2 is a side elevational view with the top in open position, the other side being substantially the same;

FIG. 3 is a front elevational view thereof;

FIG. 4 is a perspective view thereof with the top open, a portion of the right support bar being broken away for convenience of illustration;

FIG. 5 is an enlarged perspective view of a fragment of the fork utensil and mounting thereof, as shown in FIGS. 3 and 4; and

FIG. 6 is a fragmentary perspective view taken from the side opposite that shown in FIG. 4.

The screening portion in FIG. 1 and the grid work

shown in FIG. 4 cover the entire area between the positions shown. The bottom of the grill is essentially plain.

I claim:

The ornamental design for a grill, as shown and described.
